(Cl. D52—1)

To all whom it may concern:

Be it known that I, Rothwell R. Fluke, a citizen of the United States, residing at Cleveland, in the county of Cuyahoga and State of Ohio, have invented a new, original, and ornamental Design for a Level, of which the following is a specification, reference being had to the accompanying drawings, forming part thereof.

Fig. 1 is a perspective view of a level, showing my new design.

Fig. 2 is a side elevation.

Fig. 3 is a plan view.

Fig. 4 is an end elevation.

Fig. 5 is a section on the line 5—5 of Fig. 2.

Fig. 6 is a section on the line 6—6 of Fig. 2.

I claim:

The ornamental design for a level, as shown.

ROTHWELL R. FLUKE.
